UNITED STATES PATENT OFFICE.

ENGELBERT JAWOREK, OF CRESCENT CITY, CALIFORNIA.

LOGGING-SHOE.

1,106,098.

Specification of Letters Patent.

Patented Aug. 4, 1914.

Application filed March 12, 1914. Serial No. 824,199.

To all whom it may concern:

Be it known that I, ENGELBERT JAWOREK, a citizen of Austria, residing at Crescent City, in the county of Del Norte and State of California, have invented certain new and useful Improvements in Logging-Shoes, of which the following is a specification.

This invention relates to improvements in anti-slipping devices and more particularly to a logging shoe adapted to be worn by persons engaged in the logging business in localities where trees are cut down and thrown into a river to be floated to a destination.

15 The purpose of the invention is to provide a logging shoe so constructed as to enable the wearer to ride upon the floating logs without danger of slipping therefrom and falling into the water.

20 With the foregoing and other objects in view the invention consists in the combination and arrangement of parts to be herein-after fully described in the following specification, pointed out in the claims and illustrated in the accompanying drawings which form a part of said specification and in which—

Figure 1 is a view of my logging shoes attached to the shoes and trousers of a user. 30 Fig. 2 is a side view of the logging shoe complete. Fig. 3 is a front view of the same. Fig. 4 is a section taken on line 4—4 of Fig. 3. Fig. 5 is a bottom plan view of the device with the logging hooks removed. 35 Fig. 6 is a section taken on line 6—6 of Fig. 7. Fig. 7 is a side elevation of a portion of Fig. 5. Fig. 8 is a vertical section through a portion of the supporting rods and through the casting carrying the same and carrying 40 the hooks employed; said hooks being removed, and it is taken on line 8—8 of Fig. 9. Fig. 9 is a side view of Fig. 8 taken on line 9—9 of that figure. Fig. 10 is a section taken on line 10—10 of Fig. 8.

45 Like reference characters indicate corresponding parts throughout the several views.

The reference numeral 1 denotes a sole plate provided with spikes 2 and with buckles 3, 3 to which the toe-straps 4 are fastened that pass over the toe of the shoe of the wearer to help to retain the sole plate in

operative position. To the heel of the sole plate which is formed with a pair of transverse slots disposed in the same plane I secure a pair of oppositely disposed angle 55 plates 5, 5 which project above said heel and are apertured in alinement with each other to permit passage therethrough of a bolt 6 which also passes through the shoe 6^a of the user and is retained in adjusted position by 60 means of thumb screws 7, 7.

To the under surface of the instep of the logging shoe I secure a casting 8 formed with oppositely disposed angular sockets 9, 9^a and with ears 10, 10 to which oppositely 65 disposed braces 11, 11 are pivoted which rise above the shoe and which are provided with straps 12 that carry leather girdles 13 by means of which the braces are secured to the trouser legs of the wearer to better retain 70 the shoes in position. Into the sockets 9, 9^a the hooks 14, 14^a are terminally projected and secured in position by screws or other suitable fastening means 15. The construction of the hooks 14, 14^a is such as to enable 75 the user to obtain a purchase upon the floating logs and thus retain his equilibrium.

What is claimed is:—

1. In a logging shoe, a sole plate provided with spikes, toe-straps secured to said sole 80 plate, heel fastening means secured to said sole plate, a casting secured to the instep of said sole plate, supporting arms, provided with girdles, secured to said casting and anti-slipping means operatively associated 85 with said casting.

2. In a logging shoe, a sole plate provided with spikes, toe-straps secured to said sole plate, adjustable heel fastening means secured to said sole plate, a casting secured to 90 the instep of said sole plate and formed with oppositely disposed angular sockets, shoe supporting means secured to said casting and oppositely disposed hooks terminally embedded in the sockets of said casting. 95

In testimony that I claim the foregoing as my own I have hereto affixed my signature in the presence of two subscribing witnesses.

ENGELBERT JAWOREK.
